US00D467236S

(12) **United States Design Patent**
Takita et al.

(10) Patent No.: **US D467,236 S**
(45) Date of Patent: ** Dec. 17, 2002

(54) **DIGITAL AUDIO DISC RECORDER WITH
CASSETTE RECORDER**

D410,923 S * 6/1999 Ito et al. D14/156
D432,111 S * 10/2000 Takahashi D14/156
D439,236 S * 3/2001 Ito et al. D14/168

(75) Inventors: **Haruki Takita, Tokyo (JP); Yasunobu
Shimizu, Tokyo (JP)**

* cited by examiner

(73) Assignee: **Teac Corporation, Tokyo (JP)**

Primary Examiner—Nanda Bondade
(74) Attorney, Agent, or Firm—Kanesaka & Takeuchi

(**) Term: **14 Years**

(57) **CLAIM**

(21) Appl. No.: **29/152,998**

The ornamental design for a digital audio disc recorder with cassette recorder, as shown and described.

(22) Filed: **Jan. 7, 2002**

DESCRIPTION

(30) **Foreign Application Priority Data**

Jul. 17, 2001 (JP) 2001-020898

(51) LOC (7) Cl. **14-01**

(52) U.S. Cl. **D14/168**

(58) **Field of Search** D14/135-136,
D14/156-157, 160-164, 167-168, 188,
193-198, 257-258; 369/75.1, 75.2, 77.1,
77.2; 455/344, 347, 350-351

(56) **References Cited**

FIG. 1 is a front view of a digital audio disc recorder with cassette recorder showing our new design;

FIG. 2 is a top plan view thereof;

FIG. 3 is a bottom plan view thereof;

FIG. 4 is a left side view thereof;

FIG. 5 is a right side view thereof;

FIG. 6 is a rear view thereof; and,

FIG. 7 is a perspective view thereof.
